STARTING ARRANGEMENT FOR INTERNAL COMBUSTION ENGINES

Albert. Callsen, Stuttgart-Botnang, and Adolf Weiss, Marbach-on-the-Neckar, Germany, assignors to Robert Bosch Gesellschaft mit beschränkter Haftung

Application March 17, 1937, Serial No. 131,472
In Germany March 27, 1936

13 Claims.

(CL. 74—7)

The present invention relates to a starting arrangement for internal combustion engines of the type in which a pinion connected by a clutch to the starter shaft is brought into and out of mesh with a driven element by an axial displacement.

In starting arrangements of this type it often occurs that the coupling element, such as the pinion, is moved back along its threaded spindle too soon, and in consequence comes too soon out of mesh.

According to the present invention a retaining element is provided for the coupling element, such as a pinion which is directly or indirectly released by a control element.

The invention is more particularly described in the accompanying drawings in which:

Figure 1 is a sectional elevation of one form of construction.

Figure 2 is a similar view with the parts in another position.

Figure 3 is a sectional elevation of an alternative form of construction.

Figure 4 is a view similar to Figure 3 with the parts in another position.

Figure 5 shows diagrammatically the circuit of the starting devices.

Figure 6 is an enlarged fragmentary view partly in section, of one end of the starter device illustrated in Figs. 1 and 2.

An electric starting motor 10 has its armature shaft 11 extended, and is provided at the end of this shaft with a third bearing. A threaded sleeve 12 is freely rotatable on this shaft, and is provided with two threadings 13, 14. A pinion 15 is mounted on the threading 13, whilst an abutment nut 16 is mounted on the threading 14, and bears against the element of a plate clutch.

The plate clutch consists of the aforesaid nut 16, a drum 17 keyed to the armature shaft, and a plurality of friction discs 18 disposed between these parts; it also comprises an abutment plate 19 and a spring abutment 20. The drum 17 is of such a length that it extends over the friction discs.

The control element 21 consists of a bolt 23 secured to a rod 22. This rod is guided through the hollow armature shaft 11 of the starting motor, and extends from the end thereof opposite the pinion 15, and is at this end provided with an armature 24 of an electromagnet 25, which simultaneously acts as a switch, which electromagnet 25 is adapted to draw the rod 22 in and out of the armature shaft when its circuit is completed.

When the circuit of electromagnet 25 is open, the rod 22 is pushed by means of a spring 26 into the armature shaft in a direction contrary to its pull by electromagnetic force. The bolt 23

which is mounted on the rod 22 extends through a longitudinal slot 27 in the hollow armature shaft, and lies, as has already been indicated, behind the nut 16 to displace this against a stop flange 28 on the threaded sleeve 12.

Between this stop flange 28 and a flange on the nut 16, a spring 29 is disposed, which tends to press the nut against the clutch plates. The slots 27 are of such length that when the rod 22 is drawn back, the bolt 23 can move as far as the abutment 20 of the friction discs, so that the abutment or pressure plate 19, which is thicker than this bolt, comes to rest against abutment 20.

At the outer end of the sleeve 12, a flange 30 is provided to which is secured a spring coupling element 31. This spring coupling element is so disposed that it engages between a pair of the teeth of the pinion when this is meshing with the toothed ring 32 on the engine fly-wheel. The flange 30 and the sleeve 12 are mounted on the flanged end 33 of shaft 11.

A switch element 34 is disposed above the pinion 15, which switch is closed when this pinion is fully meshed with the toothed ring on the fly-wheel. This switch is disposed in the circuit of the electromagnet 25.

The motor circuit (see Fig. 6) includes a battery 110, one terminal of which is grounded and the other terminal of which is connected by an electromagnetic switch 111, controlled by a push-button or starter switch 112, and resistance 113, connected in parallel with motor switch 114, to one terminal of the electric starter motor 10, the other terminal of which is grounded. One contact of switch 34 is grounded and the other contact is connected to one end of the electromagnet coil 25, which controls electromagnetic switch 114, the other end of said coil being connected to the circuit between switches 111 and 114.

The operation of the device is as follows:

In order to start the engine, the driver switches on the starting motor 10 by closing push-button or starter switch 112 and this in turn operates electromagnetic switch 111 to close the circuit to the electric motor 10 through resistance 113. The threaded sleeve 12 will be turned by the shaft 11 only however, through the friction existing between the flanged element 33 and this sleeve 12. The pinion mounted on this sleeve will then screw up along its threading due to its inertia, and when it engages against the flange 30 the spring coupling 31 will snap between a pair of its teeth, and simultaneously therewith the switch 34 is closed, closing the circuit of electromagnet 25, whereby the motor switch 114 is closed to bridge or short-circuit resistance 113, and consequently the starting motor is given its full voltage. The magnet 25 draws the rod 22 with the bolt 23 back into the

position shown in Figure 2, and thus releases the nut 16, so that this can now screw up against the friction discs and become displaced with the friction discs until arrested by the abutment 20. The friction disc coupling is then fully operative as a power coupling, and can transmit full torque on the starting motor.

Should, during the starting period, the internal combustion engine momentarily accelerate, the pinion 15 will not come out of mesh, because it is held by the locking element 31. As soon however, as the engine is fully started the automatic release of the clutch takes place and the sleeve 12 catches up with the armature shaft. The pinion is still however, not yet put out of mesh. This will only occur when the driver breaks the circuit of the starting motor, and with it the circuit of the electromagnet. When the circuit of the electromagnet is open the spring 20 will press the rod 22 against the nut 16, and also the sleeve 12 by means of the abutment flange 28 against the flange element 33. By this means, the friction between the starter shaft 11 and the sleeve 12 on the flange 33 has so increased with the resistance of the locking element 31 that the pinion is overcome, with the consequence that this pinion is then free to come out of mesh. In order to aid release of the button or locking element 31 from engagement with pinion 15, the flanks of the teeth on the front side or edge of said pinion are beveled as indicated at 15a in Fig. 6. By reason of the beveled flanks, the button 31 is depressed and released as soon as the momentum exerted on the pinion upon overrunning of the motor has reached a certain amount.

In this form of construction, the same control element operates the friction disc coupling, and also controls unmeshing of the pinion.

In the second form of construction shown by way of example in Figures 3 and 4, a locking element is provided which is brought into the locking position indirectly by means of the control element, and is also again freed by this control element. As in the first form of construction, the pinion is mounted on a threaded sleeve 40, which is connected to the hollow starter shaft 41 through a friction disc clutch 42. The threaded sleeve has two threadings, one for the pinion, and the other for the abutment nut 43 of the friction disc coupling. This friction disc coupling comprises in addition to the nut 43 a drum 46 mounted on the starter shaft 41, a number of friction discs 47 disposed between the said drum and nut and an abutment 48 for these friction discs. The sleeve 40 is axially displaceable in two bearings 44 and 45. At the inner end of the sleeve a stop flange 49 is provided adapted to engage the abutment 48 when the pinion is fully in mesh. Two stops 50 and 51 are disposed respectively at the outer end and at the middle of this sleeve 40, which limit the movement of the pinion on the sleeve. A hole 52 is disposed in the sleeve 40 between these stops 50 and 51, in which a locking element comprising a ball 53 can lie. This hole is so disposed that the root of the toothed threading on the pinion lies over it when it lies against the projection 50.

A control rod 54 is axially displaceable within the sleeve and hollow shaft which extends through the starter at the opposite end to the driving side, and is there provided with an armature 55 of an electromagnet in order to displace the rod against the pinion when the circuit of the electro-magnet has completed. The con-

trol rod is adjacent to the end where the pinion is disposed, a flange 56 having a bevelled or conical end surface which, in the position of rest of the starter, and also in the position in which the pinion is out of mesh and the circuit of the electromagnet is open, lies directly behind the hole 52 in which the ball 53 lies. The rod 54 is drawn back into the position of rest by means of a spring 57 disposed between a shoulder 58 on the armature shaft and a flange 59 on this rod. A spring 60 is provided which is adapted to draw back the sleeve into its position of rest when the starting operation is completed. A switch 61 is disposed over the pinion in a similar manner to that described with reference to Figures 1 and 2, which switch is operated by the pinion and is in the circuit of the windings of electromagnet controlling the armature 55.

In this second form of construction, the following operations occur at starting:

On the closing of the starter switch, the sleeve 40 is turned by the friction discs lightly engaged by reason of the spring 60. The pinion mounted upon that sleeve screws up along it, due to its inertia, and engages with the toothed ring 62 of the fly-wheel until it comes up against the annular stop 50. In this position, as shown in Figure 4, the switch 61 is closed by this pinion, and consequently, the electromagnet is excited. The control rod 54 is in consequence displaced against the pressure of the spring 57 and the ball 53 is lifted by reason of the bevelled surface of the flange 56 and is held in this position by this flange. The ball can, in this position of the pinion, move outwards in the sleeve when this pinion lies at the outer end of the threading. The sleeve is displaced against the bearing 44 by the pinion, as it abuts against the stop 50. In consequence the stop 49 at the inner end of the sleeve moves against the abutment 48 of the friction disc clutch. This friction disc clutch can then transmit the full torque of the starter, as the friction discs are pressed by the nut 43 with full force against the abutment. Should the internal combustion engine spurt forward, the pinion is not put out of mesh, as this is prevented by means of the ball. The pinion therefore, is driven by the fly-wheel, but this drive will not be transmitted to the armature, as the clutch acts as a free-wheel. Only when the driver has opened the circuit of the electromagnet will the lock formed by the ball 53 be released, as the rod 54 is drawn back by the spring 57, and thus allows the ball to move inwardly.

We declare that what we claim is:

1. An internal combustion engine starter comprising a prime-mover, means to automatically couple the prime-mover to the engine on operation of the prime-mover, means to lock the coupling between prime-mover and engine during the whole time of operation of the prime-mover, and electromagnetically-controlled means to release the coupling between engine and prime-mover only on cessation of operation of the prime-mover.

2. An internal combustion engine starter comprising an electric motor, an element driven by said motor, means to couple said element to the engine automatically upon closure of the circuit of said electro-motor and an electromagnetically-controlled lock to maintain said coupling during the total time of closure of said electric motor circuit.

3. An internal combustion engine starter com-

prising an electric motor, a coupling element between said electric motor and the engine automatically engaged on the closing of the circuit of said electric motor, a slipping clutch between said electric motor and the coupling element driven thereby, electromagnetically-controlled means to engage said clutch fully to transmit total torque of said motor only when the coupling is fully engaged, means to lock said coupling when fully engaged, and means to disconnect said locking means only on breaking of the electric motor circuit.

4. An internal combustion engine starter comprising an electric motor, a driving element driven thereby, means to automatically clutch said driving element to said engine on the closing of said motor circuit, locking means for said driving element, an electromagnetic control means for said locking means, and means to release said locking means on the breaking of the motor circuit.

5. An internal combustion engine starter comprising an electric motor, a driving element driven thereby, means to automatically clutch said driving element to said engine on the closing of said motor circuit, locking means for said driving element, electromagnetic control means for said locking means, a switch controlling said electromagnetic control means, means to close said switch and the circuit of said electro-magnet when said clutch is fully engaged, means to break the circuit of said electro-magnet on the breaking of the motor circuit, and spring means to disconnect said locking means on the breaking of said circuits.

35 6. An internal combustion engine starter comprising an electric motor, a driving element driven thereby, means to automatically clutch said driving element to said engine on the closing of said motor circuit, locking means for said driving element, electromagnetic-control means for said locking means, a switch controlling said electromagnetic control means, means to close said switch and the circuit of said electro-magnet when said clutch is fully engaged, means to break the circuit of said electro-magnet on the breaking of the motor circuit, and spring means to disconnect said locking means on the breaking of said circuits, a friction clutch between the driving element driven by the electric motor and said electric motor, means to control said friction clutch, so that it transmits full torque only when the element driven from said electric motor is fully engaged with the engine, and means to release said friction clutch simultaneously with the release of the locking means and the breaking of the circuits of said electric motor, and electromagnet.

7. An internal combustion engine starter comprising an electric motor, a threaded sleeve driven thereby, a pinion threaded on said sleeve and axially displaceable thereon by reason of its inertia, a toothed starter ring connected to the engine, a friction clutch between the said sleeve and said electric motor, means including an electromagnet and controlled by the axial displacement of said pinion for controlling said clutch, whereby said clutch only transmits maximum torque when said pinion is fully engaged with said toothed ring, a lock preventing axial displacement of said threaded sleeve and pinion when the pinion is fully engaged with said ring, said electromagnet

controlling said lock, and means to break the circuit of said electromagnet and said motor simultaneously.

8. An internal combustion engine starter comprising an electric motor, a threaded sleeve driven thereby, a pinion in threaded engagement with and axially displaceable along said sleeve by reason of its inertia, a friction clutch between said sleeve and said electric motor, automatic torque control means for said clutch whereby the full torque of said electric motor is only transmitted thereby upon full axial displacement of said pinion, locking means between said pinion and said sleeve, a toothed ring on said engine engaged by said pinion when fully displaced axially, an electro-magnet controlling said locking means, a switch controlling the circuit of said electro-magnet and operated by said displaceable pinion, and means to simultaneously break the circuit of said electro-magnet and said electric motor.

9. An internal combustion engine starter comprising a motor, a threaded shaft driven by said motor, a driving member in threaded engagement with said shaft for axial displacement thereon to automatically engage and disengage said engine, and electromagnetically-controlled means for preventing disengaging movement of said driving member during operation of said motor.

10. An internal combustion engine starter comprising an electric motor, a threaded shaft driven by said electric motor, a pinion in direct threaded engagement with said shaft for axial displacement thereon to automatically engage and disengage a gear member of an engine to be started, and means for locking said pinion in engagement with said engine gear member until after de-energization of said electric motor.

11. An internal combustion engine starter comprising an electric motor, a threaded shaft driven by said motor, a clutch between said motor and said shaft, a driving member in threaded engagement with said shaft for axial displacement thereon to automatically engage and disengage said engine, and electromagnetically-controlled means for controlling the operation of said clutch and for preventing disengaging movement of said driving member until after de-energization of said electric motor.

12. An internal combustion engine starter comprising a motor, a threaded shaft driven by said motor, a driving member in threaded engagement with said shaft for axial displacement thereon to automatically engage and disengage said engine, a stop member to lock said driving member in its engaged position, and electromagnetically controlled means to release said stop member from its locking position.

13. An internal combustion engine starter comprising an electric motor, a threaded shaft driven by said electric motor, a driving member in threaded engagement with said shaft for axial displacement thereon to automatically engage and disengage a member of the engine to be started, a stop member to lock said driving member in its engaged position, and electromagnetically-controlled means for preventing release of said stop member from locking position until after de-energization of said electric motor.
